UNITED STATES PATENT OFFICE.

ANNE E. TOMLINSON, OF NEW YORK, N. Y.

DESIGN FOR LADY'S BELT.

No. 37,969.

Specification for Design.

Patented April 24, 1906.

Application filed December 9, 1905. Serial No. 291,154. Term of patent 3½ years.

To all whom it may concern:

Be it known that I, ANNE E. TOMLINSON, a citizen of the United States, residing at 101 Waverly Place, in the city, county, and State of New York, have invented a new, original, and ornamental Design for Ladies' Belts, of which the following is a specification, reference being had to the accompanying drawing, forming a part thereof.

The figure is a plan view of a lady's belt, showing my new design.

I claim—

The ornamental design for lady's belt as shown.

ANNE E. TOMLINSON.
